United States Rubber Company, New York, N. Y., a
corporation of New Jersey

Application July 18, 1955, Serial No. 37,007

Term of patent 14 years

(Cl. D90—20)

Fig. 1

Fig. 2

*Fig. 3**Fig. 4*Fig. 1 is a perspective view of a tire embodying my new design, it being understood that the design is repeated throughout the circumference of said tire;

Fig. 2 is an enlarged fragmentary plan view of a section of the tread of the tire;

Fig. 3 is an enlarged fragmentary side elevation of the side wall of the tire; and

Fig. 4 is a sectional view through the tire taken substantially on the plane indicated by line IV-IV in Fig. 2.

The dominant features of my design consist in the portions shown in full lines.

I claim:

The ornamental design for a tire, substantially as shown and described.
